(57) CLAIM

The ornamental design for a decorative walker, as shown and described.

DESCRIPTION

FIG. 1 is a front perspective view of a decorative walker. FIG. 2 is a right side perspective view thereof; and, FIG. 3 is a left side perspective view thereof.

The broken lines on FIGS. 1, 2 and 3 represent a walker and form no part of this invention.

1 Claim, 3 Drawing Sheets

FIG. 1

FIG. 3
